Primary Examiner — Rachel A. Voorhies(74) *Attorney, Agent, or Firm* — Merchant & Gould P.C.(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of the display screen with graphical user interface, showing a color image; and,

FIG. 2 is a front view of a second embodiment thereof. Except as indicated herein, the black dashed broken lines and dot-dot broken lines show portions of the display screen with graphical user interface that form no part of the claimed design. The dot-dash lines represent the display screen and also represent a boundary of the claimed design, and form no part of the claimed design.

The blue dashed broken lines representing 5% and 95% in the Ambulatory Glucose Profile region of FIG. 1 are part of the claimed design.

1 Claim, 2 Drawing Sheets
(1 of 2 Drawing Sheet(s) Filed in Color)

AGP Report

Name _____

MRN _____

GLUCOSE STATISTICS AND TARGETS

26 Feb 2019-10 Mar 2019
% Time CGM is Active18 days
99.5%

Glucose Ranges

Target Range 70-180 mg/dL ..... Greater than 70% (16hr 48min)
Below 70 mg/dL ..... Less than 4% (58min)
Below 54 mg/dL ..... Less than 1% (14min)

Above 250 mg/dL ..... Less than 5% (1hr 12min)

Each 5% increase in time in range (70-180 mg/dL) is clinically beneficial.

Average Glucose

175 mg/dL

Glucose Management Indicator (GMI)

7.9%

Glucose Variability

50.5%

Defined as percent coefficient of variation (%CV); target <36%.

TIME IN RANGES

AMBULATORY GLUCOSE PROFILE (AGP)

AGP is a summary of glucose values from the report period, with median (50%) and other percentiles shown as if occurring in a single day.

DAILY GLUCOSE PROFILES

Each daily profile represents a midnight-to-midnight period.
